UNITED STATES PATENT OFFICE

123,298

DESIGN FOR A CASING FOR A PROJECTOR

Isreal J. London, Detroit, Mich.

Application March 8, 1940, Serial No. 90,775

Term of patent 7 years

To all whom it may concern:

Be it known that I, Isreal J. London, a citizen of the United States, residing at Detroit, in the county of Wayne and State of Michigan, have invented a new, original, and ornamental Design for a Casing for a Projector, of which the following is a specification, reference being had to the accompanying drawings, forming a part thereof:

In the drawings,

Figure 1 is a top plan view of the casing for a projector showing my new design;

Figure 2 is a bottom plan view of the casing for a projector;

Figure 3 is a side elevational view of the casing for a projector;

Figure 4 is a front elevational view of the casing for a projector; and

Figure 5 is a rear elevational view thereof.

I claim:

The ornamental design for a casing for a projector, substantially as shown.

ISREAL J. LONDON.
